OPEN SIDED GOLF BAG

Lester H. Hamley, Pendleton, Oreg.

Application March 30, 1953, Serial No. 345,620

3 Claims. (Cl. 150—1.5)

This invention relates generally to carriers for golf clubs and particularly to an "open sided golf bag."

The main object of this invention is to provide a light weight, inexpensive and convenient means for carrying clubs without danger of marring or mutilating the clubs and, at the same time, making them instantly available in a fanned out fashion when the bag is permitted to occupy a horizontal position on the ground.

The second object is to make a bag which is especially adapted to carry clubs when a caddy or golf bag cart is not available or desirable.

I accomplish these and other objects in the manner set forth in the following specification as illustrated in the accompanying drawings, in which:

Fig. 1 is a side elevation showing a man carrying the bag by means of a hand grip.

Fig. 2 is a section taken along the line 2—2 in Fig. 1.

Fig. 3 is a plan of the bag as it appears lying flat on the ground and open.

Fig. 4 is a section taken along the line 4—4 in Fig. 3.

Fig. 5 is a section taken along the line 5—5 in Fig. 4.

Fig. 6 is a view similar to Fig. 1 but showing the bag held by means of the shoulder straps.

Fig. 7 is a view similar to Fig. 3, showing the manner of attaching the shoulder straps.

Fig. 8 is a fragmentary section through a shoulder strap connecting grommet.

Fig. 9 is a perspective view of one of the supporting straps.

Like numbers of reference refer to the same or similar parts throughout the several views.

Referring in detail to the drawing, there is shown a short cylindrical section 10 of leather provided with a bottom 11 of fairly rigid material. A liner 12 is placed around the inside of the section 10 and a covering 13 is placed over the bottom 11.

From the edge 14 extends an elongated flap 15 which is roughly pear-shaped. This portion is only one thickness of leather except for the large end 16 which has a lining of leather.

Hand holes 17 are formed in opposite sides of the large portion of the flap 15. A pocket 18, preferably provided with a "zipper" 19, is provided on the side of the section 10 for carrying golf balls, tees, etc.

2

It will be noted in Fig. 3 that the clubs 20 and 21 are fanned out when the flap 15 is permitted to open, making each of the clubs readily accessible for selection and extraction, whereas in Fig. 2 it will be seen that the clubs 5 are all gathered into a compact bundle by merely passing a hand through both of the hand holes 17.

It is desirable to provide an additional facing 22 along the edge 14 to provide a little extra stiffness and hold the cylindrical shape at the mouth of the section 10.

10 In Fig. 7 it will be seen that the large end 16 is provided with a liner 23 in which are a pair of grommets 24 on opposite sides of the center seam 25. Along the edges 26 of the portion 15 are the spaced grommets 27 which are near the center of balance of the golf bag.

Shoulder straps 28 having end snaps 29 and 30 engage the grommets 27 and 24, respectively, on opposite sides of the member 15.

An inspection of Fig. 7 discloses the fact that when the bag is laid down on the green, the clubs will fan out in a way to make them easily selectable and the shoulder straps will swing free of the clubs instead of becoming fouled therewith.

In Fig. 6 is shown the manner in which the bag is carried by means of the two straps 28 slung from the shoulder of the player. For transportation purposes the snaps 29 and 30 may pass through the grommets on opposite sides of the carrier, serving to hold them in an enclosed form, should this be desired.

I claim:

30 1. An open-sided golf bag comprising a short cylindrical bottom portion having one side extending upwardly in the shape of an elongated pear-shaped flap forming the upper portion of the bag, the lower end of said flap adjoining said cylindrical bottom portion being narrow and extending around approximately only one half the circumference of said bottom portion and the upper end of said flap being of greater width and sufficiently flexible to open out laterally substantially flat when the bag is laid on the ground.

35 2. A golf bag as defined in claim 1 having a pair of hand holes in opposite sides of the upper, wide end of said flap for folding said opposite sides together when both hand holes are grasped in one hand.

40 3. A golf bag as defined in claim 1 having a pair of shoulder straps on opposite sides of said flap, one strap being attached at upper and lower points to one side of the flap and the other strap being attached at upper and lower points to the opposite side of the flap.
